UNITED STATES PATENT OFFICE.

RALPH E. HEISEL, OF CHILlicothe, Ohio, ASSIGNOR, BY MESNE ASSIGNMENTS, TO
PAPER MACHINERY CORPORATION, OF DAYTON, OHIO, A CORPORATION OF OHIO.

PAPER-MAKING MACHINERY.

Application filed May 25, 1925. Serial No. 32,688.

The present invention relates to apparatus for making paper, and more particularly to that portion of the apparatus which has to do with the flowing of the paper-making stock or pulp to form a sheet or web of paper.

One of the principal objects of the invention is to provide a stationary deckle for a moving wire upon which the paper is formed.

Other objects and advantages of the invention will be apparent from the following description when taken in connection with the accompanying drawings, in which;

Fig. 1 is a plan view of a device embodying the present invention;

Fig. 2 is a side elevation of the device shown in Fig. 1;

Fig. 3 is an enlarged detail, partly in section, taken on the line 3—3 of Fig. 1;

Fig. 4 is a perspective view showing a detail of construction;

Fig. 5 is a somewhat diagrammatic view to illustrate the operation of the present invention;

Fig. 6 is a fragmentary detail view, in section, of the adjusting mechanism, on the line 6—6 of Fig. 3; and

Fig. 7 is a view similar to Fig. 3 showing a second form of the invention.

As showing a preferred embodiment, the invention is illustrated in connection with a Fourdrinier type of paper-making machine. In a machine of this type the pulp or other fibrous material suspended in water, and hereinafter referred to generally as pulp, is supplied to a flow-box, whence it is fed through a suitable opening at the desired rate across a flow-directing apron on to a traveling wire, which may or may not be given a transverse oscillatory motion, this wire being endless and suspended upon two rotatable rolls, the roll at the flow-box or inlet end being called the breast roll, and the roll at the other or outlet end of the wire being generally called the couch roll.

In the drawing the flow-box is indicated generally at 20, the endless wire at 21 and the breast roll for the inlet end of the wire at 22. It will be understood that the wire, or wire-cloth which is a screen of fine mesh wire, passes over the breast roll 22 in the direction indicated by the arrow, so that, when the wire reaches the upper side of the

breast roll it travels in a direction away from the flow-box 20. As is usual in apparatus of this type, the wire passes over a series of supporting or tube rolls 23, and over suction devices or boxes 24, and thence over a couch roll, which couch roll is not illustrated herein.

The flow-box 20 is provided with an outlet opening through which the pulp flows from the flow-box and is uniformly distributed upon the wire. The outlet of the flow-box comprises an apron 25 adapted to overlie the inlet end of the wire, and a lip or plate 26 spaced from the apron 25 to provide a relatively narrow slot or opening for the flow of the pulp on to the wire. For purposes of simplicity of description this outlet opening is shown as of constant width being closed by end plates such as illustrated at 27, but of variable height so as to vary the thickness of pulp which is permitted to flow upon the wire.

As is well understood in the art the function of a deckle is to restrain lateral spread of the pulp upon the wire to thus retain the pulp within an area of a given width upon the wire while the water is being extracted and the paper being formed, so that the web or sheet of paper coming from the wire will be of a predetermined width. The present invention provides a stationary deckle means for the wire, that is, a deckle which is stationary with the frame work of the machine, and does not travel with the wire. The deckle means comprises a deckle rail 30 supported upon a plurality of supporting tubes 31, which tubes are pivotally mounted as at 32 upon suitable brackets 33 carried upon the side frame 34 of the machine. Referring to Fig. 3, it will be seen that the supporting tubes 31 extend laterally from the side frame of the machine over the wire 21, so as to support the deckle rail 30 above the wire 21. Each bracket is provided with an adjusting screw 35 for adjusting the height of the deckle rail 30 from the wire 21 and a locking screw 36 for locking each bracket in said adjustable position. To permit moving of the deckle rail 30 laterally over the wire in order to vary the width of the web of paper the supporting tube 31 is provided with adjusting means consisting of an adjusting screw 37 rotatably mounted in suitable bearings within the tube 31.

Threadedly mounted on the screw 37 is an internally threaded collar 38 which has an arm extending through slot 39 in the tube 31 and secured to the deckle rail 30 to support the latter. The collar 38 also has an external or ring portion 40 surrounding the tube 31, this ring portion carrying a locking screw 41 by which the parts may be locked in their adjusted positions upon the tube 31.

5 A bevel gear 42 is mounted upon the outer end of each of the adjusting screws 37, each of these gears meshing with a cooperating beveled gear 43, the several gears 43 being mounted upon the actuating shaft 44. The actuating shaft 44 is supported from the bracket 33 by means of the brackets 45 and may be provided with a crank 46 or other suitable means whereby the actuating shaft may be rotated to effect simultaneous movement 10 of the several adjusting screws so as to move the deckle rail 30 to any desired position. Only one side of the paper-making machine, and therefore only one deckling arrangement is shown. But, of course, both sides of the machine are provided with the deckle arrangement, the apparatus on opposite sides being exactly alike in construction except for necessary reversal of parts. Of course, the two deckle arrangements should 15 give smooth, parallel edges to the paper and the means for moving the deckle rails is therefore so constructed that the rails on opposite sides of the machine are at all times parallel to each other.

20 35 Mounted upon the deckle rail 30 and rigidly secured thereto by means of suitable brackets 50 are a number of pipes 51 by which water, air or other suitable fluid may be led to the deckle arrangement under pressure. As best shown in Fig. 3, the lower portion of the deckle rail 30 is beveled from its lower inner edge outwardly and upwardly at an angle of approximately 45 degrees. The pipes 51 are provided with a 25 series of apertures or openings 52 which are so disposed as to discharge water or air upon the wire 21, the same being caused to impact with the wire 21 underneath the lower edge of the deckle rail 30 and preferably adjacent the intersection of the inner surface of the rail with the wire.

30 While the form of apparatus shown and described above has been found to give extremely satisfactory results while functioning as a deckle arrangement to limit the lateral spread of the pulp upon the forming wire in such wise as to produce a sheet of paper having substantially smooth parallel edges, nevertheless the precise arrangement 35 shown is not necessary for practising applicant's invention. The pulp as it is flowed on to the wire is quite fluent and tends to readily spread in all directions. To secure a sheet of paper of the desired width it is 40 therefore necessary to prevent undue lateral spread of the pulp. And in this invention this lateral spread is prevented by directing a flow of water, or other fluid under pressure against the pulp upon the wire to overcome its inherent tendency to spread. Of course 45 the lateral spread of the pulp may be quite positively restrained by the use of a solid wall, such as the conventional rubber deckle strap. But such a strap results in rapid wear of the wire, and has other undesirable 50 features. The rigid stationary deckle rail 30 described above functions as a positive limiting wall to prevent the lateral spread of the pulp. If such a rail were maintained in contact with the wire the wear would be 55 much more rapid than with the conventional rubber deckle strap. But by providing such a rail, and spacing it a slight distance above the wire—and this distance need only be sufficient to avoid actual contact of the 60 wire and the rail—and directing a flow of water into the space between the rail and the wire lateral spread of the pulp may be prevented. In the arrangement shown with the beveled lower portion of the rail the restraining water is directed downwardly 65 against the wire, into the small clearance between the rail and the wire and the pressure water thus injected, through the kinetic energy due to its pressure, builds up what is 70 in practical effect a continuation of the rigid rail 30, although this continuation because of its mobility avoids all of the objectional features that would be present were the rail actually brought in contact with 75 the wire. It is apparent that the invention is not limited to the use of water, but that any suitable fluid, such as air, may be employed for this purpose. The deckle rail 30 may be adjusted vertically so as to increase 80 or decrease the gap between the wire and the deckle rail, thereby varying the line or zone of action of the impact fluid upon the wire and upon the edge of the pulp. In the embodiment of the invention illustrated, the 85 fluid is shown as directed against the wire in lateral direction at an angle of approximately 45 degrees, as illustrated in Fig. 3, and at an angle of 60 degrees to the wire in the direction of travel of the latter, as shown in 90 Figs. 2 and 5. It will be apparent, however, that the pressure of the fluid and its direction of application, as well as the distance of the openings 52 from the wire, are subject to variation, these factors being more or 95 less interdependent upon one another.

100 And while the deckle rail 30 is provided as a convenient means for varying the line of action of the impact fluid upon the edge of the pulp, it may be stated that its function and adjustment depends somewhat upon the pressure, direction, and point of application of the impact fluid and that by suitable control and application of the fluid, the positioning of the deckle rail 30 may be widely 105 110 115 120 125 130 135 140

varied or even entirely omitted in some cases. Such a construction in which the deckle rail has been omitted is illustrated in Fig. 7, from which it will appear the fluid pipe 51 is carried directly by the collar or ring 40. The construction of the supporting tubes 31, supporting brackets, and adjusting means for this form of the invention may be the same as illustrated in Figs. 1 to 10, from which it is apparent that the fluid tube 51 may be adjusted vertically or horizontally relatively to the forming wire to vary the action or point of application of the impacting fluid as desired.

15 The fluid conduit is illustrated in the drawing as consisting of three short pipes 51 which connect separately with the source of fluid, and are controlled separately by the valves 53, the purpose of this construction being to insure a better control of fluid pressure in the pipes and upon the wire, but it will be understood that the pipes may be increased in number, or decreased in number, as desired, upon so proportioning the same 25 as to insure the delivery of the fluid in the desired manner along the several points of the wire.

20 The pivotal connection 32 between the tubes 31 and the brackets 33 is such that the tubes 31, the parts carried thereby, and the entire adjusting means constitute a unitary structure which may be swung upwardly and outwardly about 32 as a pivot so as to not interfere with the free upward movement of the wire 21 when it is desired to move the same from the machine for replacement or repair.

25 As already stated the deckle means including the deckle rail 30 is movable so as to vary the width of the web of paper being formed. In order to direct the flow of the pulp coming through the outlet of the flow-box 20 and to prevent the same from flowing to the outer side of the deckle rail, there is provided an adjustable connection between the end of the deckle rail and the outlet of the flow-box. This adjustable connection, as best illustrated in Fig. 4, comprises a curved closure plate 60 which cooperates with the end plate 27 the apron 25 and the lip 26 to close the end of the effective outlet opening. An L-plate extension or tongue 61 extends from the closure plate 60 and is adapted to receive the end of the deckle rail 30. An ear 62 is also mounted on the closure plate 60 adjacent the upright portion of the extension 61, and at a distance somewhat greater than the width of the rail 30, which, when the device is assembled, is positioned between this ear and the upright portion of the extension. By means of this arrangement undue lateral separation of the rail and the extension is prevented; and, in addition, the rail during lateral adjusting movement cooperates with the ear or the

extension to cause concomitant movement of the closure plate. The closure plate 60 may be adjusted relative to the apron 25 and lip 26 of the outlet opening by adjusting means 63, and then securely clamped in position 70 upon the apron 25 by the clamping means 64.

75 From the foregoing it will be apparent that the present invention provides a stationary deckle means for a traveling wire, the deckle means being simple in construction and easily adjustable to any desired position. The deckle maintains the pulp within the proper area when it is flowed upon the wire, and until sufficient water has been removed from the pulp for the web of 80 paper to take a permanent set. Ordinarily the deckle need not extend beyond the suction boxes 24, sufficient water having ordinarily been removed from the pulp by the time it reaches the suction boxes to make 85 further use of a deckle unnecessary. By means of this invention the desired restraining of the lateral spread of the pulp and resulting control of the width of the sheet of paper being formed is secured without 90 any solid part of the deckle means being brought into contact with the wire. Consequently there is a very material increase in the life of the wire, there being no excessive wear upon the latter at the deckle edge 95 as in the case of the previously known form of deckle means, this being an item of considerable importance in the maintenance of the machine owing to the great cost of the wires. A further advantage of the present 100 invention is to increase the output of the machine owing to the fact that the same may be operated continuously for longer periods than heretofore without the necessity for stopping the machine to change 105 wires.

110 While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended 115 claims.

What is claimed is:

1. In the making of paper in paper-making apparatus having a forming wire and means for flowing pulp upon said wire, the method of confining the pulp to a predetermined area upon the wire by controlling the lateral spread thereof, which method consists in impinging a fluid on said wire at the edge of said area. 129

2. In the making of paper in paper-making apparatus having a forming wire and means for flowing pulp upon said wire, the method of confining the pulp to a predetermined area upon the wire, which method 130

consists in directing a flowing stream of fluid against the pulp upon the wire to prevent the lateral spread of such pulp.

3. In the making of paper in paper-making apparatus having a traveling wire and means for flowing pulp upon said wire to form a web of paper thereon, the method of controlling the width of said web upon the wire, which method consists in impinging a fluid upon the wire along a line substantially coextensive with the intended edge of said web of paper, to restrain lateral spread of the pulp on the wire.

4. In paper making apparatus, a wire, means for flowing pulp upon said wire, and deckle means associated with the wire for limiting lateral spread of the pulp upon the wire, said deckle means comprising a stationary deckle member spaced from said wire.

5. In paper making apparatus, a wire, means for flowing pulp upon said wire, and deckle means associated with the wire for limiting lateral spread of the pulp upon the wire, said deckle means comprising a stationary deckle member spaced from said wire, and means for impinging a fluid upon the wire adjacent the stationary deckle member.

6. In paper making apparatus, a wire, means for flowing pulp upon said wire, and deckle means associated with the wire for limiting lateral spread of the pulp upon the wire, said deckle means comprising a rail above the wire and spaced therefrom, the rail having its lower edge beveled, and means for impinging a fluid upon the wire along the line of said beveled edge.

7. In paper making apparatus, a wire, means for flowing pulp upon said wire, and deckle means associated with the wire for limiting lateral spread of the pulp upon the wire, said deckle means comprising a rail above the wire and spaced therefrom, the lower edge of the rail being beveled outwardly and upwardly from the edge thereof facing the pulp, and means on the outer side of said rail for impinging a fluid between the wire and the lower edge of the rail.

8. In paper making apparatus, a wire, means for flowing pulp upon said wire, and deckle means associated with the wire for limiting lateral spread of the pulp upon the wire, said deckle means comprising a rail above the wire and spaced therefrom, the rail having its lower edge beveled, and means for impinging a fluid upon the wire at an angle of approximately 45 degrees to the wire.

9. In paper making apparatus of the character described, a traveling wire, means for flowing paper-forming stock upon said wire, and deckle means associated with said wire for restraining lateral spread of the stock upon said wire, said deckle means comprising

ing a stationary deckle member out of contact with said wire, and means for supplying fluid between said deckle member and the wire for restraining spread of the stock upon the wire.

70

10. For use in paper making apparatus having a wire and means for flowing pulp upon said wire; deckle means comprising a rail, means for supporting said rail above the wire in spaced relation thereto, and means associated with said rail for flowing a fluid along said rail to limit lateral spread of the pulp upon the wire.

75

11. In paper making apparatus, a traveling wire, means for flowing pulp upon the wire to form a continuous web thereon, and stationary deckle means at all times out of contact with the wire for controlling the lateral spread of the pulp upon the wire.

80

12. In paper making apparatus, a traveling wire, means for flowing pulp upon the wire to form a continuous web thereon, and deckle means for controlling the lateral spread of the pulp upon the wire, said deckle means comprising a stationary deckle member positioned above and in spaced relation to the wire along the edge of the web.

85

13. In paper making apparatus, a traveling wire, means for flowing pulp upon the wire to form a continuous web thereon, and deckle means for controlling the lateral spread of the pulp upon the wire, said deckle means comprising a stationary deckle member positioned above the wire and spaced therefrom, and means for adjusting the position of the deckle member relative to the wire.

90

14. In paper making apparatus, a traveling wire, means for flowing pulp upon the wire to form a continuous web thereon, and deckle means for controlling the lateral spread of the pulp upon the wire, said deckle means comprising a stationary deckle member positioned above the wire, and bracket means for supporting the deckle member in position, said bracket means being so constructed and arranged as to permit the deckle member and bracket means to be moved bodily out of the path of the wire to permit the upward removal of the latter.

105

15. In paper making apparatus, a traveling wire, means for flowing pulp upon the wire to form a continuous web thereon, and deckle means for controlling the lateral spread of the pulp upon the wire, said deckle means comprising an elongated stationary deckle member positioned above the wire, means for supporting the deckle member, and means for moving the elongated deckle member as a whole transversely of its length, whereby to vary the width of the web.

110

16. In paper making apparatus, a moving wire, means for flowing pulp upon the wire to form a continuous web thereon, and deckle means for controlling the lateral

120

125

130

spread of the pulp upon the wire, said deckle means comprising an elongated stationary deckle rail positioned along the edge of the web, means for supporting the elongated rail, a plurality of adjusting devices for moving the elongated rail laterally whereby to vary the width of the web, and a common means for actuating said adjusting devices in unison, said elongated rail, the supporting means therefor, the adjusting means therefor, and the actuating means, being constructed as a unit and so connected with the frame of the paper making apparatus as to permit upward removal of the wire 15 while maintaining said connection with the frame work of the apparatus.

17. In paper making apparatus of the character described, a traveling wire, means for flowing paper-forming stock upon said wire, and deckle means for restraining lateral spread of the stock upon said wire, said deckle means comprising means for impinging a fluid spray on said wire at the edge of said stock.

25 18. In paper making apparatus of the character described, a traveling wire, means for flowing paper-forming stock upon said wire, and deckle means for restraining lateral spread of the stock upon said wire, said deckle means comprising a pipe connected to a source of pressure fluid and extending above the said wire, said pipe having perforations to direct a fluid spray along the edge of said stock to limit the spread of the 35 stock.

19. For use in paper making apparatus of the character described having a traveling wire and means for flowing paper-forming stock upon said wire; deckle means for restraining the lateral spread of stock upon said wire, said deckle means comprising a perforated pipe for positioning above said wire and adapted for connection to a source of pressure fluid to direct a fluid spray along 40 the edge of said stock to limit the spread of the stock.

20. In a paper making machine, a traveling wire, means for flowing pulp upon the wire to form a continuous web thereon, a stationary deckle member positioned above the wire, and a tiltably mounted support for said deckle member adapted to effect adjustment of the vertical position of said deckle member relative to the wire.

55 21. A paper-making machine comprising a movable sieve; and means for regulating the width of the paper pulp comprising fixed boundary strips arranged a slight distance above the sieve track, and adjustable transversely, and tubes at the side of the boundary strips for forcing a fluid under pressure in the space between the boundary strips and the paper track.

22. A paper-making machine comprising

a movable sieve; and means for regulating 65 the width of the paper pulp comprising fixed boundary strips arranged a slight distance above the sieve track, and tubes at the side of the boundary strips for forcing water streams under pressure in the space between 70 the boundary strips and the paper track.

23. A paper-making machine comprising a movable sieve; and means for regulating the width of the paper pulp comprising fixed boundary strips arranged a slight distance 75 above the sieve track, and tubes at the side of the boundary strips for forcing fluid streams under pressure obliquely forward in the direction of the movement of the sieve in the space between the boundary strips and 80 the paper track.

24. A paper-making machine comprising a movable sieve; and means for regulating the width of the paper pulp comprising fixed boundary strips, carriers between which the 85 strips are removably arranged, said strips being arranged a slight distance above the sieve track, and tubes at the side of the boundary strips for forcing a fluid pressure in the space between the boundary strips and 90 the paper track.

25. In a paper making machine, web forming means, a dam or deckle for stock on said web forming means, means for supplying fluid under pressure along the web forming 95 means adjacent the dam or deckle, and means for controlling the volume of fluid under pressure delivered on the web forming means adjacent said dam or deckle.

26. In a paper making machine, web forming means, a dam or deckle for stock on said web forming means, nozzle means for delivering fluid under pressure along the web forming means adjacent said dam or deckle, and means providing for adjustment of the 105 dam or deckle with respect to the web forming means.

27. In a Fourdrinier paper making machine, a normally stationary dam or deckle for stock on the wire part, means for delivering fluid under pressure along the wire part adjacent said dam or deckle, means for adjusting the dam or deckle and the fluid delivering means vertically with respect to the wire, and means providing for adjustment 115 of the dam or deckle and said fluid delivering means laterally of the wire.

28. A deckle having an elongated nozzle for delivering fluid under pressure along the web forming part of a paper making machine.

29. A hollow deckle structure terminating at its lower portion in nozzle means for delivering deckling fluid along the web forming part of a paper making machine.

In testimony whereof I hereto affix my signature.

RALPH E. HEISEL
